VALVE.

1,176,769.

Specification of Letters Patent.

Patented Mar. 28, 1916.

Application filed June 20, 1914. Serial No. 846,223.

To all whom it may concern:

Be it known that I, DANIEL B. MEDANICH, a citizen of the United States, residing at Buechel, in the county of Jefferson and State 5 of Kentucky, have invented certain new and useful Improvements in Valves, of which the following is a specification.

This invention relates to valves for use in motors, and more especially to valves adapted 10 to be used with explosive motors.

An object is to provide a valve which will be efficient and durable in service, and which will be perfectly balanced.

Another object is to provide a valve, of 15 the piston type, which being surrounded by a water jacket will operate under better conditions than the ordinary valve.

A further object is to provide a valve adapted, when serving as an exhaust valve, 20 to be air cooled internally.

With the foregoing, and other objects in view the invention consists of the novel construction and arrangement of parts illustrated in the accompanying drawing, which 25 forms a part of this specification, in which is set forth an embodiment of the invention, but it is to be understood that changes, variations and modifications may be resorted to which come within the scope of the appended 30 claims.

Referring to the drawing, Figure 1, is a sectional view of a portion of an explosive motor with my valve applied, in elevation, as an exhaust valve; Fig. 2, is a side elevation 35 of the same portion of the motor as Fig. 1; Fig. 3 is a view the same as Fig. 1, but showing the valve in section and open; Figs. 4 and 5, are respectively elevation and bottom plan of means for turning the valve on its 40 axis.

In the drawing —1— designates a cylinder within which a piston —2—, of usual construction, operates. In Fig. 1, the piston is represented as being on the downward, or 45 power stroke, the exhaust valve —3— being closed; in Fig. 3, the piston is represented as on the up, or exhaust stroke, driving out the products of combustion through the exhaust valve which is open. The valve is 50 tubular and adapted to be incorporated within a bore —4— of a cylinder —5— which is preferably, formed integral with the main cylinder. A water jacket —6— envelops the main and valve cylinders. The valve

cylinder is open, at its lower end, to the atmosphere, and at its upper end has a flange —7— for the attachment of an exhaust pipe. An annular channel —8—, near the upper end of the bore 4, encircles the valve 3 and serves to lead the gases, from the main cylinder, around the valve subjecting the valve to equal pressure on all sides and avoiding unequal wear, due to side pressure. Brackets —9— and —10— extended from the side of the main cylinder serve as guides for a 65 valve rod —11—. The rod 11 is attached to the valve in such manner that the valve may rotate on the rod, the arrangement illustrated being as follows: On the upper end of the valve rod is a spherical enlargement, 70 or ball —12—. A flanged cup —13—, fitting about the rod and over the ball is secured to a diaphragm —14—, positioned within and above the medial line of the valve, and serves to hold the rod in flexible 75 connection with the valve. This method of connecting the rod to the valve not only permits the valve to turn independent of the rod, but assures that the valve will travel freely in the bore 4, even though the rod 80 should be slightly out of alinement, due to wear in the bearings, or other cause. A spring —15— coiled about the valve rod and resting on the bracket 9 and pressing against the diaphragm 14 serves to hold the valve 85 closed, and to return it to the closed position when opened. A bell-crank lever —16—, having a long arm —17— and a short arm —18—, is so positioned that the long arm will engage an angular projection —19— on the lower end of the valve rod and open the 90 valve.

A cam —20—, secured on a shaft —21—, receives motion in the usual manner from a main crank shaft and impinging on the 95 short arm of the lever 16 acts to open the valve. As the valve descends a lever —22—, which normally stands at an angle of approximately 60 degrees, engages one of a series of projections or serrations —22'—, 100 on the lower end of the side wall of the valve, the arrangement being such that as the lever assumes a horizontal position, being forced down by the valve, the valve will be turned a distance equal to the spacing of the 105 serrations. The valve is prevented from overthrowing, or turning a distance greater than the width of a serration, by the end 108

the lever binding on the bracket 9 while the point —23— binds in the serrations. The point 23 extends above the plane of the lever the entrant angle thereof being substantially the same as that of the serrations. As the valve ascends, the lever 22 is returned to its normal position by a spring —24—, or the overweighted end —25— (as shown in Fig. 4). The arrangement just described is such that each time the valve closes it seats in a changed position thus insuring equal wear on the seats. A spring —26—, coiled about the valve rod, and resting on the bracket 10, serves to cushion the descent of the valve, a collar —27—, attached to the valve rod, striking on the spring. The valve is open at the lower end to the atmosphere and the diaphragm 14 is pierced with a plurality of perforations —28—. A series of ribs —29— are positioned between the diaphragm and the top of the valve and communicating with the interior thereof. A tube —30— secured in the upper end of the valve extends up into the exhaust passage —31—. As the products of combustion are forced out, through the passage 31, the rush thereof past the orifice of the tube 30 draws a current of air up through the piston which flowing over the large radiating surface presented by the ribs 29 serves to lower the temperature of the head of the valve to a point which is conducive to the longevity of the valve seat.

It is thought that the many advantages, and the method of construction and use can be thoroughly understood from the foregoing without more extended description.

Having thus described my invention so that any one skilled in the art pertaining thereto may make and use the same, I claim:

1. In mechanism of the class described, a valve, a valve rod to which said valve is rotatably connected, means operable to engage with the advance edge of said valve and partially rotate same during its opening movement.

2. In mechanism of the class described, a tubular valve, a valve rod to which it is rotatably connected and mechanical means adapted to engage the advance edge of said valve and positively rotate same a predetermined distance during the opening movement thereof.

3. A valve cylinder, a tubular piston valve positioned therein, said valve open at its lower end to the atmosphere, and a tube in the upper end thereof extending into the exhaust passage.

4. In an explosive motor, a power cylinder, a valve cylinder, said valve cylinder having an internal annular recess communicating with the power cylinder, a tubular piston valve open at its lower end positioned in said valve cylinder, a tube in the upper end of the valve extending into the exhaust

passage, a spring for closing said valve, and means for partially turning said valve at each reciprocation thereof.

5. In an explosive motor, a power cylinder, a valve cylinder having a lateral opening communicating with the power cylinder, said valve cylinder being open at its lower end to the atmosphere and having an exhaust passage leading from its upper end, a tubular valve positioned in said valve cylinder and adapted to be reciprocated to open and close said lateral opening and exhaust passage, said valve being open at its lower end to the atmosphere.

6. In an explosive motor, a power cylinder, a valve cylinder communicating with the power cylinder, said valve cylinder being open at its lower end to the atmosphere and having an exhaust passage leading from its upper end, a tubular valve positioned in said valve cylinder and adapted to be reciprocated to open and close said exhaust passage, said valve being open at its lower end to the atmosphere, and a tubular projection extended from the upper end of the valve into said exhaust passage.

7. In an explosive motor, a power cylinder, a valve cylinder communicating with the power cylinder, said valve cylinder being open at its lower end and having an exhaust passage leading from its upper end, a tubular valve positioned in said valve cylinder and adapted to be reciprocated to open and close said exhaust passage, said valve being open at its lower end to the atmosphere, a plurality of serrations on the side wall of said valve at the open end thereof, a pawl adapted to engage with said serrations, and a tubular projection extended from the upper end of the valve into said exhaust passage.

8. In an explosive motor, a power cylinder, a valve cylinder having an exhaust passage leading from the upper end thereof, the lower end thereof being open to the atmosphere, an internal annular tapering valve seat in the upper end thereof, a tubular piston valve, the head whereof is adapted to close on said seat, said valve being open at its lower end to the atmosphere, and a tube extended from its upper end into said exhaust passage whereby escaping gases draw air through said piston to cool same.

9. In an explosive motor, a power cylinder, a valve cylinder, having an exhaust passage leading from its upper end, the lower end thereof being open to the atmosphere, an internal annular valve seat in the upper end thereof, a tubular piston valve, the head whereof is adapted to close on said seat, a valve rod to which said valve is rotatably connected, said valve being open at its lower end to the atmosphere, and a tube extended from its upper end into said exhaust pas-

sage whereby escaping gases draw air through said piston to cool same.

10. In an explosive motor, a power cylinder, a valve cylinder having an exhaust passage leading from its upper end, the lower end thereof being open to the atmosphere, an internal annular valve seat in the upper end thereof, a tubular piston valve; the head whereof is adapted to close on said seat, means engageable with said valve to partially rotate same during its opening movement, said valve being open at its lower end to the atmosphere, and a tube extended from its upper end into said exhaust passage whereby escaping gases draw air through said piston to cool same.

11. In an explosive motor, a power cylinder, a valve cylinder having an exhaust passage leading from its upper end, the lower end thereof, being open to the atmosphere, an internal annular valve seat in the upper end thereof, a tubular piston valve, the head whereof is adapted to close on said seat, a valve rod connected to said valve by means of a ball and socket joint, said valve being open at its lower end to the atmosphere, and a tube extended from its upper end into said exhaust passage whereby escaping gases draw air through said piston to cool same.

12. In an explosive motor, a power cylinder, a valve cylinder having an exhaust passage leading from its upper end, the lower end being open to the atmosphere, an internal annular valve seat in the upper end thereof, a tubular piston valve, the head whereof is adapted to close on said seat, serrations on the lower end of the valve, a pawl adapted to engage with said serrations and partially rotate said valve during its opening movement, said valve being open at its lower end to the atmosphere, and a tube extended from its upper end into said exhaust passage whereby escaping gases draw air through said piston to cool same.

13. In an explosive motor, a valve cylinder open at one end to the atmosphere having an exhaust passage leading from the other end in a prolongation of the axis thereof, a tubular piston valve positioned within said cylinder the head whereof is adapted to close said exhaust passage, the outer end of said valve being open to the atmosphere, a valve rod to which said valve is rotatably

connected, a series of projections on the outer end of the side wall of said valve and means adapted to engage said projections and partially rotate said valve during the opening movement thereof.

14. In an explosive motor, a power cylinder, a valve cylinder having an exhaust passage leading from the upper end, the lower end thereof being open to the atmosphere, an internal annular valve seat in the upper end thereof, a tubular piston valve, the head whereof is adapted to close on said seat, means engageable with said valve to partially rotate same during its opening movement, and a valve rod to which said valve is rotatably connected.

15. In an explosive motor, a power cylinder, a valve cylinder having an exhaust passage leading from the upper end, the lower end being open to the atmosphere, an internal annular valve seat in the upper end thereof, a tubular piston valve, the head whereof is adapted to close on said seat, a valve rod connected to said valve by means of a ball and socket joint, and means for partially rotating said valve at each opening stroke.

16. A valve cylinder open at one end to the atmosphere, a tubular piston valve likewise open to the atmosphere positioned within said cylinder, serrations on the side wall of said valve at the open end thereof and means engageable with said serrations to partially rotate said valve during the opening movement thereof.

17. A valve cylinder open at one end to the atmosphere, a tubular piston valve likewise open to the atmosphere positioned within said cylinder, serrations on the end of the side wall of said valve at the open end thereof, and a pawl adapted to engage with said serrations to partially rotate said valve during the opening movement thereof.

18. A valve cylinder, a tubular piston valve open at one end to the atmosphere positioned therein, means adapted to engage with the side wall of said valve at the outer end thereof and partially rotate same during its opening movement.
